UNITED STATES PATENT OFFICE.

PETER NEUKIRCHEN, OF CHICAGO, ILLINOIS.

HANDED FOLDING RULE.

1,097,350.

Specification of Letters Patent. Patented May 19, 1914.

Application filed May 29, 1913. Serial No. 770,591.

To all whom it may concern:

Be it known that I, PETER NEUKIRCHEN, a citizen of the United States, and a resident of Chicago, county of Cook, and State of Illinois, have invented certain new and useful Improvements in Handled Folding Rules, of which the following is declared to be a full, clear, and exact description.

This invention relates to drawing instruments, and has for its principal object to provide a simple, cheap and efficient instrument having combined therein, a tubular handle, foldable rule sections arranged to be slid into said handle or withdrawn therefrom to form a twelve inch rule, a pencil and a knife supported in said tubular handle, and either capable of being slid out through the open end of said tubular handle, for use.

The invention consists in the several novel features of construction, arrangement and combination of parts hereinafter fully set forth and claimed.

The invention is clearly illustrated in the drawing furnished herewith, of which—

25 Figure 1, is a side view of a drawing instrument embodying the one form of the present invention, showing the rule extended; Fig. 2, is a side view of the instrument looking at the side opposite to that viewed in Fig. 1, but showing the rule slid into the handle, and the knife blade extended to a position ready for use; Fig. 3, is a longitudinal section taken on the line 3—3 of Fig. 2; Fig. 4, is 30 a longitudinal section taken on the line 4—4 of Fig. 3, and showing the rule in a partly extended position; Fig. 5, is a detail, cross section taken on the line 5—5 of Fig. 3, Fig. 6, is a detail, cross section taken on the line 6—6 of Fig. 4, the handle being omitted, Fig. 7, is a detail, cross section taken on the line 7—7 of Fig. 1, and Fig. 8, is a detail longitudinal section taken on the line 8—8 of Fig. 4.

45 Referring to said drawing, 10, designates a tubular handle open at both ends, and having a longitudinally extending, centrally located partition 11, secured thereto in any suitable manner, as for instance by soldering it to the handle. The partition is shown as formed with marginal flanges 12, that bear against the inner wall of the tubular handle, and said flanges may be soldered to the handle. Said partition is formed 50 with a longitudinally extending slot 13, through which extends a rivet 14, for slid-

ably connecting the foldable rule sections with the partition. As shown, the rule comprises four sections 15, 16, 17, 18, which are marked with linear divisions, and the sections 16, 17, are pivoted together, as at 19, while the sections 17, 18, are pivoted together, as at 20; the arrangement being such that the end section 18, may be folded back upon the section 17, and thereafter the sections 17, 18, may be folded back over the section 16, as seen in Fig. 4, and when all three parts have been brought into a position, side by side, they may be slid into the tubular handle on one side of the partition. 60 The slot 13, of the partition 11, is of such length that when the foldable sections of the rule have been fully extended, the divisions on the handle 10, and foldable sections of the rule form a continuous twelve inch 65 scale.

Slidably mounted within the handle, on the side of the partition 11, opposite the side containing the foldable section of the rule, is a knife and pencil holder 21, which 70 supports a pencil 22, at one end, and a knife blade 23, at its other end. Said knife and pencil holder fits within that half of the tubular handle on one side of the partition 11, and has a knob 24, secured to it, 75 which extends out through a longitudinally extending slot 25, in the tubular handle, said knob furnishing means whereby the pencil and knife support may be shifted back and forth to bring the pencil into operative position beyond one open end of the handle and the knife beyond the other open end thereof. The knob 24, is formed on the end of a headed stem, which extends through the pencil and knife holder 21, and is headed 80 on the inner side thereof, as seen in Fig. 7. A hole 26, is formed in the tubular handle at some point diametrically opposite the slot 25, for the insertion of a tool in heading or upsetting the inner end of the stem of the 85 knob 24. One end of the tubular handle is formed with a notch 10^a, and the end section 18, of the rule, is formed with a bent end 90 18^a, to facilitate the withdrawal of the foldable sections of the rule.

105 Preferably the rule section 16, is struck up near the rivet 14, to form projections 30, and the partition 11, is likewise struck up at points near the ends of the slot 13, to form sockets or depressions 31, 32, which are arranged to receive the projections of the rule section, when at the limits of its extended 110

or retracted position, thereby forming a lock between the rule sections and handle to prevent accidental relative movement therebetween.

5 The instrument is exceedingly cheap, simple in construction, and yet very useful, since it combines many tools that may be contained in a small compass, making the instrument easy to carry about in a person's

10 pocket.
More or less variation of the exact details of construction is possible without departing from the spirit of this invention, and I do not, therefore, desire to limit myself to
15 the exact construction shown and described, except as may be necessitated by the prior state of the art.

I claim as new and desire to secure by Letters Patent:

20 1. A handled folding rule, comprising a tubular handle having a longitudinally slotted, centrally located partition, rule sections pivoted together and slidably connected to said longitudinally slotted parti-
25 tion.

2. A handled folding rule, comprising a tubular handle, a longitudinally slotted partition, centrally located therein, a plurality of rule sections pivoted together, and a slide- 30 able connection between one of said fold-
able rule sections and the slotted partition, said tubular handle and foldable rule sec-
tions bearing linear divisions extending from end to end.

3. In a handled folding rule, a handle 35 having a longitudinally slotted partition se-
cured therein, said partition being formed with depressions near the ends of the slot, and foldable rule sections, pivoted together, 40 one of the end sections being slidably con-
nected to said partition by a rivet, secured to the rule and extending through said slot, said rule section having a projection near said rivet, arranged to enter the depressions in the partition.

PETER NEUKIRCHEN.
